Primary Examiner — Paula Allen Greene(74) *Attorney, Agent, or Firm* — Kilpatrick Townsend & Stockton LLP**CLAIM**

The ornamental design for the headphone, as shown and described.

DESCRIPTION

FIG. 1 is a front perspective view of the headphone showing our new design;

FIG. 2 is a front elevation view thereof;

FIG. 3 is a rear elevation view thereof;

FIG. 4 is a top plan view thereof;

FIG. 5 is a bottom plan view thereof;

FIG. 6 is a right-side elevation view thereof; and,

FIG. 7 is a left-side elevation view thereof.

The broken lines depict portions of the headphone that form no part of the claimed design.
